A. H. DAVIS

SASH OR STORE FRONT CONSTRUCTION

Filed Nov. 2, 1926

UNITED STATES PATENT OFFICE.

ARCHIBALD H. DAVIS, OF LINCOLN, NEBRASKA.

SASH OR STORE-FRONT CONSTRUCTION.

Application filed November 2, 1926. Serial No. 145,824.

The present invention relates to metal moulding adapted for use in sash or store front constructions.

My object is to provide a simple construction of moulding and tensioning means adapted for use in connection with the pane of a sash or store front, to the end that the front piece may have a constant tension against the pane in an even manner, to prevent breakage of the pane when it is being set, and to permit vibration, expansion and contraction without disturbing the permanency of the setting or holding of the pane and yet to make it possible to tension any parts of the moulding which require adjustment after the installation has been made.

Another object is to dispense with moulding-tensioning screws that enter the jamb or sill, in a store front construction, and thus obviate the disadvantages incident to constructions of that character.

My improvements comprise the combination with a front piece or moulding, preferably of such gauge as to be substantially non-yielding, of a flexible, tensile bearing plate or clips, whether of light or heavy material, said bearing plate, or clips being anchored toward the rear of the front part thereof so that the front part thereof may flex to a greater or lesser degree according to the nature of the embodiment of my improvements, and a screw which holds the front moulding in position and against the front of the pane without interfering with the shock-absorbing action of the flexible, tensile bearing plate. In such a construction, the flexible bearing plate or clips may yield to a greater or lesser degree, even to the extent of canting somewhat upwardly, when the pane or glass vibrates, expands or contracts, thereby causing the front piece or moulding to be held against the pane and yet permitting it to have a flexing action to take care of expansion and contraction and any movements of the pane after it has been set and to enable the desired tension to be obtained at different points of the length of the moulding by adjustment effected from the front of the moulding.

A sash or store front construction embodying my improvements may be fastened to the sill or to the jamb or, in the case of a sash construction, be wholly self-contained.

Furthermore, while I prefer to employ clips or separate pieces, suitably spaced apart in

the direction of the length of the moulding, as the flexible bearing plate and to provide tension screws to connect the respective clips to the front moulding, nevertheless, the flexible bearing plate may be continuous and connected at suitably spaced points to the front moulding by tension screws, or other fastening means.

The present invention is characterized by the automatically-acting spring-cushion or shock-absorber means which enables the mouldings to permit the pane to vibrate, expand, or contract without disturbing the setting of the pane or permitting injury thereto.

Only certain forms which the invention may assume are illustrated in the accompanying drawings and hereinafter described. It will be understood, however, that no attempt has been made to illustrate all of the forms in which the invention is susceptible of embodiment as considerable variation may be resorted to without departing from the spirit of the invention.

In the accompanying drawings:

Figure 1, is a vertical section showing one form of the invention combined with a sill and stop;

Fig. 2, is a similar view of another form combined only with a sill;

Fig. 3, is a similar view of another form, dotted lines showing the tensile action and how the parts may flex or bend;

Fig. 4, is a similar view of an embodiment wherein the front and back moulding are of relatively heavy gauge;

Fig. 5, is a similar view of another modification wherein the front moulding is of light gauge stock and the rear moulding of heavy gauge metal;

Fig. 6, is a detail plan view of the flexible bearing plate of Figs. 2 and 3; and

Fig. 7, is a detail elevation of the flexible bearing plate of Fig. 1.

Referring first to Fig. 1, the invention is shown embodied in a store front construction, 100 1 representing the sill and 2 is a stop piece. As shown, these are of wood. The pane appears at 3.

The sill may have metal sheathing 4.

The outer moulding is shown at 5, being of metal stock of any desired ornamental contour and adapted to have its upper part bear against the pane 3, said upper part being provided with a down-turned flange where it bears on the pane.

The lower part of the moulding 5 is extended inwardly and rests on the sill 1 or on the sheathing 4, as the case may be.

My improved flexible, tensile bearing plate 6 is located inside of the moulding 5 and beneath the pane 3.

As shown in Fig. 1, the flexible, tensile bearing plate 6 has its front part lying on the inturned lower part of the moulding 5 but 10 is not connected thereto. The flexible, tensile bearing plate 6, which appears in front elevation in Figure 7 has a downwardly bent part 7 so that it may rest at its rear or inner part on the sheathing 4 or on the sill 1 as the 15 case may be. The rear part of the flexible, tensile bearing plate 6 extends upwardly as shown in Figs. 1 and 7 and is connected to the stop 2 by screws 8.

The upwardly extending front part of the 20 bearing plate 6 has a screw threaded aperture, preferably an internally screw threaded hub 9.

A fastening screw 10 extends through an 25 opening in the front of the moulding 5 and is engaged with the screw threaded part 9.

In Fig. 2, the construction illustrated in Fig. 1 is modified by the elimination of the stop 2 and the provision of a metal back stop 2^a to take the place of said stop 2. The 30 sheathing 4 is extended upwardly at 4^a to lie against the back stop. Instead of the flexible, tensile bearing member extending upwardly at the rear and secured by the screw 8 as shown in Fig. 1, in the construction appearing in Fig. 2, the flexible, tensile bearing plate appears at 11 and it, and the back stop, are secured by screw 12.

The fastening screw 10 is provided as 40 shown in Fig. 1. A block or blocks may be used to support the pane 3 in the construction shown in Fig. 2, as represented by dotted lines.

Fig. 6 shows in plan view the flexible, tensile bearing plate of Fig. 2.

Fig. 3 illustrates the same construction as shown in Fig. 2 except that the front moulding, the back stop, and the flexible, tensile bearing plate 11 are secured to the sill 1 without any sheathing 4, 4^a, being provided.

The flexible, tensile bearing plate 6 of Fig. 1 and 11 of Figs. 2 and 3 is preferably of 50 spring brass, there being provided as many of these bearing plates as may be necessary.

The bearing plates, either 6 or 11, are free 55 to flex and tension throughout their length from their point of anchoring by the fastening screw 8, or 12. Consequently, when the screws 10 are tightened or eased at different points, there will be a flexing tension of these 60 bearing plates so that the moulding will be seated evenly against the pane 3 and will be adapted to yield to take care of expansion and contraction or vibration as illustrated by dotted lines in Fig. 3.

65 The gauge of the material of the bearing

plates may vary. They may be of heavier gauge than the moulding 5 or of the same gauge or, as will presently appear, they may be of lighter gauge than the moulding and back stop. This, however, is governed by 70 the amount of pressure and flexibility required against the pane or glass through the outer or front moulding.

Being free for the greater part of their length, the bearing plates have an improved 75 action and better capacity for performing their purposes than tensioning or clamping constructions of which I have knowledge.

In the construction shown in Fig. 4, the front moulding 13 and the rear moulding 14 80 are of heavier gauge than the flexible bearing plates 16. The bearing plates 16 may be riveted to the rear moulding 14 at 17 and as many of these bearing plates used as may be found necessary or they may be continuous. 85

To facilitate the adjustment of the heavy gauge moulding 13, it is preferably rounded at 15 to rock on the front part of the base of the rear moulding 14 and it may be rounded at its upper part where it engages the pane 3. 90 Any suitable means may be employed to secure the moulding 14 to the sill, back stop, or sash proper.

My invention as described in connection with Figs. 1, 2, 3, 4, contemplates the use of 95 individual or separate flexible tensile bearing plates located at intervals of the length of the moulding, thereby doing away with the necessity of cutting and fitting continuous inner pieces which are used in securing the parts of 100 a sash or store front moulding together. These forms also eliminate the cost of manufacture and of stocking and shipping continuous and long inner moulding connecting pieces.

However, there are installations which may demand a continuous strip to serve as a flexible tensile bearing plate, in lieu of a plurality of flexible tensile bearing plates, as shown in Fig. 5, a form of the invention which may 110 be resorted to. In Fig. 5, the front moulding appears at 18, being of relatively light gauge. The rear moulding and the flexible bearing plate 24 are formed in a single continuous piece running lengthwise of the sash 115 or store front construction, said piece being of relatively heavy gauge. The tension screw 10 is provided and the action is, in general, the same as heretofore described except that the free part of the tension plate from its 120 point of connection or anchoring in an outward direction is shorter. As shown, screws 22 and 23 are provided to secure the plate or bar 24 to the sill 1 and stop 2 but the screw 22 might be omitted.

The piece 21 connects with the upper edge 125 of the plate or bar 24, bears against the rear of the pane, and is continued downwardly and underneath the plate or bar 24 as shown at 19, being held by the screw 22.

The tension screws 10 will be provided in the form shown in Fig. 5 at such points lengthwise of the construction as may be desired.

5 I am aware that the invention may assume other forms than the forms I have illustrated. Therefore, except where specified in the claims, I do not limit the invention to the details of construction shown and described.

10 What I claim, is:

1. In a sash or store front construction, the combination with a front moulding, of a flexible hinging tensioning and cushioning bearing member located back of said front moulding and anchored rearwardly of its outermost part, said bearing member being otherwise free to flex throughout its extent, and fastening means connecting said bearing member to the front moulding.

20 2. In a sash or store front construction, the combination with a front moulding, of a flexible hinging tensioning and cushioning bearing member located back of said front moulding and anchored rearwardly of its outermost part, said bearing member being otherwise free and having an upstanding part and adapted for flexing throughout its extent, and fastening means connecting said upstanding part to the front moulding.

25 3. In a sash or store front construction, the combination with a front moulding, of a flexible hinging tensioning and cushioning bearing member located back of said front moulding and anchored rearwardly of its outermost part, said bearing member being otherwise free and adapted to flex upwardly and downwardly in hinging fashion throughout that part of its length from its rear which extends from its anchorage toward the front

30 moulding, and fastening means connecting said bearing member to said front moulding.

4. In a sash or store front construction, the combination with a front moulding, of a flexible hinging tensioning and cushioning anchored bearing member located back of said front moulding and comprising a base part disposed in the bottom part of said sash or store front construction, and an upstand-

45 ing part connected to said base part, and fastening means disposed angularly to said upstanding part and connecting it to the front moulding, said bearing member being adapted to flex upwardly and downwardly in hinging fashion.

55 5. In a sash or store front construction, the combination with a front moulding, of a flexible hinging tensioning and cushioning anchored bearing member located back of said front moulding and comprising a base

60 part disposed substantially parallel to the bottom part of said sash or store front construction, and an upstanding part connected to said base part, said bearing member being free throughout its extent from its point of anchorage to, and including, said upstanding

part, and fastening means disposed angularly to said upstanding part and connecting it to the front moulding, said bearing member being adapted to flex upwardly and downwardly in hinging fashion.

70 6. A sash or store front construction having front and rear mouldings which have a flexible tensioning cushion joining them together below where they bear on the pane, thereby serving as a vibration and expansion 75 and contraction compensator for the pane.

7. A sash or store front construction having a front moulding or rail which is provided with a flexible tensioning cushion in the general region of its lower part, thereby 80 adapting its upper part to flexibly cushion the pane and serve as a vibration and expansion and contraction compensator for the pane.

8. In a sash or store front construction, the combination with a rear moulding, of a front moulding or rail whose upper part is adapted to bear on the pane, and a flexible hinging tensioning and cushioning joint having parts disposed angularly in relation to each other, one part being connected to the rear moulding and the other part to the front moulding.

9. In a sash or store front construction, the combination with a rear moulding, of a front moulding or rail whose upper part is adapted to bear on the pane, and a flexible hinging tensioning and cushioning joint having parts disposed angularly in relation to each other, one part being connected to the rear moulding and the other part to the front moulding, said joint embodying an adjustable connection arranged angularly in relation to one of the parts of the aforesaid joint and adapted for regulating the cushioning action of said joint.

10. In a sash or store front construction, the combination with a rear moulding, of a front moulding or rail whose upper part is adapted to bear on the pane, and a separate, flexible tensioning and cushioning bearing plate comprising flat parts disposed at an angle to each other and directly connecting the rear moulding to the front moulding or rail.

11. In a sash or store front construction, the combination with a rear moulding, of a front moulding or rail whose upper part is adapted to bear on the pane, a separate, flexible tensioning and cushioning bearing plate comprising flat parts disposed at an angle to each other, one of said parts being connected to the rear moulding, and an adjustable connection between the flexible other part of said bearing plate and the lower part of the front moulding or rail.

12. In a sash or store front construction, the combination with relatively heavy and rigid front and rear mouldings respectively adapted to bear on the front and rear faces of the pane, of a tensioned cushion co-operating with said mouldings to hold them

120

125

130

against the pane and serving as a vibration and expansion and contraction compensator for the pane.

13. In a sash or store front construction, the combination with relatively heavy and rigid front and rear mouldings respectively adapted to bear on the front and rear faces of the pane, and a tensioned cushion exerting

a constant yieldable pressure on the front moulding, thereby to hold said moulding 10 against the pane and compensate for vibration and expansion and contraction of the pane.

In testimony whereof I affix my signature.

ARCHIBALD H. DAVIS.
